(57) **CLAIM**

The ornamental design for a dialysis recharger cabinet, as shown and described.

DESCRIPTION

FIG. 1 is a perspective view of a dialysis recharger cabinet; FIG. 2 is a front view of a dialysis recharger cabinet referenced in FIG. 1;

FIG. 3 is a rear view of a dialysis recharger cabinet referenced in FIG. 1;

FIG. 4 is a left side view of a dialysis recharger cabinet referenced in FIG. 1;

FIG. 5 is a right side view of a dialysis recharger cabinet referenced in FIG. 1;

FIG. 6 is a top view of the doors of a dialysis recharger cabinet referenced in FIG. 1;

FIG. 7 is a bottom view of a dialysis recharger cabinet referenced in FIG. 1;

FIG. 8 is a cross-sectional view of a lower portion of the dialysis recharger cabinet along line 8-8 of FIG. 2; and, FIG. 9 is a cross-sectional view of a higher portion of the dialysis recharger cabinet along line 9-9 of FIG. 2.
